TAG

Marjorie C. Wilder, New York, N. Y., and John W. Rockefeller, Jr., Short Hills, N. J., assignors to Robinson Tag & Label Company, a corporation of New York

Application July 22, 1939, Serial No. 285,844

5 Claims. (Cl. 40—26)

This invention relates generally to tags but more particularly to a tag adapted to be displayed on shirts having attached collars.

It is customary to fold shirts for display or storage on the shelves or counters of a vendor's establishment by folding the arms backward and folding the bottom portion of the shirt backwardly and upwardly thus leaving the collar and the bosom displayed for inspection. It has been the usual practice, when removable tags are affixed to the shirt, to attach them to one of the buttons of the shirt with the bottom of the tag terminating adjacent the bottom folded edge of the shirt and on occasions projecting slightly beyond. As the shirts are usually stacked, one on top of the other, it is necessary to lift the bottom edge of those shirts above a shirt selected for inspection in order to inspect the tag thereon. Frequently, in grasping the lower edge of the shirt, the tag secured to the shirt next adjacent the bottom shirt which is so lifted, is inadvertently grasped resulting in tearing the tag from the shirt. Likewise in lifting shirts from various piles for packing or other purposes the tags are frequently inadvertently grasped and torn off the shirts. The reason for this is because tags so placed on a shirt are positioned where it is most natural to grasp the shirt when lifting it from the stack.

It is therefore an object of this invention to provide a tag which is adapted to be secured to a shirt at a position where it is conspicuous and yet where it is unlikely to be disturbed by handling the shirt, and more particularly to provide a tag adapted to be attached to a shirt at the junction of the collar and neck-band.

Embodiments of the invention may advantageously be formed in simulation of a bow tie and be provided near their top edges with holes having open slots to pass over the threads or shank of a collar button, and struck out tongues or tabs to engage under the collar wings. Preferably the shank or threads will be so proportioned that they will enter the slot only when the tag is at an angle to its final position, and the tabs will be lateral extensions of an integral neck so as to be capable of being folded back underneath the tag and the collar wings.

Other objects and advantages of this invention will be apparent from the specification and the accompanying drawing in which:

Fig. 1 is a front view of a shirt folded in the customary manner for stacking or packing and having the tag attached thereto;

Fig. 2 is an enlarged view of the tag shown

in Fig. 1 in its condition before being applied; and

Fig. 3 is a similar view of the tag as it appears in applied condition.

The tag will be made of suitable flexible material, such as comparatively stiff paper, and as shown is generally of a shape simulating a bow tie, the two ends 1 and 2 diverging symmetrically from the transverse center line. At the top of this center line is a slot 3, the outer corners of which are chamfered, and this slot leads into an opening 4 of a size to receive the shank of a button, the term shank being intended to comprehend threads or other attaching means.

Integrally attached to the bottom edge of the body by a neck 5 at the said center line are two oppositely extending wing-like tabs 6 and 7 struck out from the material of the tag. These tabs have a downward direction generally along the lines of the lower edges of the ends 1 and 2 and may be of a slightly curvilinear outline as shown. The top edge of the neck 5 may be scored on the rear face as indicated by the dotted line at 8, so as to provide a natural line of fold. When the neck is folded back along this line the tabs come to occupy a position against the back face of the tag as indicated by dotted lines in Fig. 3.

A shirt in usual folded condition is shown in Fig. 1. The buttons are attached by threads and as shown are two-hole buttons. The other buttons have the holes up and down, but the collar button 9 preferably has its holes arranged crosswise as shown in Fig. 1 and as indicated by dotted lines in Fig. 3. The threads therefore form an attachment 10, which for the purposes hereof may be termed a shank, which has substantially greater width than height. The width of the shank exceeds that of the slot 3, and therefore to apply the tag the tag has to be turned 90 degrees from the position shown to enter the narrow dimension of the shank 10 through the slot 3 into the opening 4, and then the tag is turned to the position shown. The neck 5 is then folded back to bring the tabs 6 and 7 under the collar wings 11 and 12, as shown in Fig. 1, in which position the tag is prevented from turning and is therefore locked on the collar button by reason of the inability of the shank 10 to enter the slot 3 in that position.

It is obvious that the particular construction shown in the drawings and above described may be variously modified within the principle and scope of our invention as defined in the appended claims. For example the slot may well be disposed at the bottom edge and one or more tabs

may be on the top edge and turned over inside the neck to prevent rotation of the tag instead of being engaged merely under the collar wings, this being in effect a reverse application of the tag from that shown.

We claim:

5. 1. A tag for use on shirts and like garments having a turn-down collar and a collar button comprising a continuous strip of readily flexible material forming an elongated body portion having a transverse slot in one long edge at substantially the center thereof for receiving the shank of the button, the strip being of such length that its ends substantially overlie the collar wings when the button shank is in the slot, and a pair of wing-like tabs attached at their inner ends to the opposite long edge and having free laterally extending wings adapted to engage a part of the garment and prevent rotation of the tag.
10. 2. A tag for use on shirts and like garments having a turn-down collar and a collar button comprising a continuous strip of readily flexible material forming an elongated body portion the two halves of which are symmetrical about the central transverse line with the lower edge of each half sloping downwardly from their inner to their outer ends, the tag having a transverse slot in the center of the top longitudinal edge to receive the button shank, and a pair of wing-like tabs struck out from the lower edge and attached thereto at their inner ends, whereby the tabs may be folded underneath the tag and engage underneath the wings of the collar when the ends of the tag overlie the wings.
15. 3. In combination with a shirt having an attached turn-down collar and collar button, a tag comprising a continuous strip of readily flexible material forming an elongated body portion with a transverse slot in the center of its top edge

into which the button shank is received with the ends of the tag overlying the collar wings, and wing-like tabs attached at their inner ends to the bottom edge of the tag and disposed underneath the collar wings.

4. In combination with a shirt having an attached turn-down collar and collar button, a tag comprising a continuous strip of readily flexible material forming an elongated body portion with a transverse slot in the center of its top edge into which the button shank is received with the ends of the tag overlying the collar wings, and a pair of wing-like tabs attached to the center of the bottom edge of the tag along a line about which they are folded back underneath the tag and engage underneath the collar wings, the said line of attachment being of a length to prevent substantial rotation of the tag about the button shank.

5. In combination with a shirt having an attached turn-down collar and a collar button the shank of which is laterally elongated, a tag of readily flexible material having an elongated body portion with a central transverse slot opening into its top edge narrower than the lateral dimension of the shank and a button hole at the lower end of the slot of a diameter exceeding the lateral dimension of the shank, the tag being disposed with the button shank in the button hole and the ends overlying the collar wings, and a pair of wing-like tabs attached to the center of the bottom edge of the tag along a line about which they are folded back underneath the tag and engage underneath the collar wings, the said line of attachment being of a length to prevent substantial rotation of the tag about the button shank.
